UNITED STATES PATENT OFFICE.

DAVID BARKER, OF LIVERPOOL, ENGLAND, ASSIGNOR TO ANDREW J. SORBELLO, OF NEW YORK, N. Y.

SECTIONAL SMOKING PIPE.

Application filed December 15, 1925, Serial No. 75,660, and in Great Britain January 3, 1925.

This invention relates to an improved tobacco pipe.

The object of the present invention is to provide a pipe which may be readily cleaned 5 by separation of the constituent parts thereof.

A further object of the invention is to provide a pipe with relatively few parts, the parts being so constructed that they are 10 easily held together on assembly.

A still further object is to provide a pipe wherein the smoke ducts are small but the smoke entering the smoker's mouth is cool and at the same time free from bits of tobacco, dirt or the like.

In the accompanying drawings:—

Fig. 1 is a longitudinal section of one form of the improved pipe.

Fig. 2 is a longitudinal section of the pipe 20 with the parts separated showing an improved form of mouth piece.

Fig. 3 is a section on the line A—B of Fig. 2.

Referring in detail to the drawings, the 25 stem portion comprises two parts 1, 2, interconnected by a dovetail tongue and groove 4, 3, the groove 3 being located preferably in the upper member 1 and the tongue 4 in the lower member 2. Formed in the 30 dovetail tongue 4 is a duct 5 forming a passage for the smoke.

At the bowl end of the stem the upper member 1 is provided with a large aperture 6 and the lower member 2 is provided with 35 a threaded aperture 7 of smaller diameter. A removable bowl 8 is provided having a connecting member 9 the lower portion of which is threaded as at 10 to engage the threaded recess 7 in the lower member 2. The 40 diameter of the upper portion of the connecting member 9 is preferably less than the diameter of the aperture 6 in the upper stem member 1 so that when the bowl is assembled on the stem an annular chamber 45 11 is formed which acts as a cooling chamber.

The hollow portion 12 of the bowl 8 adapted to receive the tobacco is located entirely above the stem members 1, 2, and is 50 connected to the annular chamber 11 by a plurality of ducts 13, for example 3, the size of the ducts being comparatively small and connecting with the upper portion of the chamber 11. Owing to the provision of the

duct 5 in the uppermost portion of the 55 lower member 2 the same connects with the lower portion of the annular chamber 11 so that a considerable cooling of the smoke will take place in the said chamber. A mouth-piece 14 of any convenient form is provided 60 and connected to the stem members 1, 2, for example by a sleeve 15.

It will be appreciated that by removal of the mouthpiece and bowl the members 1, 2, may be easily separated and cleaned together with the ducts 13 of the bowl. Further, each bowl is a complete unit and is preferably made to standard measurements so that the bowl 8 may be replaced by another bowl in the case of burning of the 70 wood or cracking of the same. Further, the provision of the cooling chamber 11 between the bowl and the stem prevents the access of small tobacco parts or moisture into the bore of the stem.

Owing to the threaded recess 7 and aperture 6 being together of greater vertical length than the threaded member 9 the screwing of the bowl into position will effectively clamp the upper portion 1 of the 80 stem in position against the lower portion 2.

I declare that what I claim is:—

1. In a tobacco pipe the combination of a stem divided longitudinally in a horizontal plane into an upper stem member and a 85 lower stem member, means to connect said members together with relative longitudinal sliding movement, a removable bowl, and means mounted on said bowl and engaging only with said lower stem member to hold 90 said members from relative sliding movement.

2. In a tobacco pipe the combination of an upper stem member provided with an aperture extending vertically therethrough, 95 a lower stem member having a threaded recess in its upper face, a removable bowl and threaded means projecting from the lower face of said bowl adapted to pass through said aperture and engage in said 100 recess to hold said stem members from relative movement.

3. In a tobacco pipe the combination of an upper stem member, a lower stem member, means to hold said members from relative 105 vertical movement, a removable bowl, and means projecting from the lower face of said bowl through said upper stem member and

engaging with said lower stem member to hold said stem members from relative horizontal movement.

4. In a tobacco pipe the combination of 5 an upper stem member having a bearing surface at one end of its upper face and an aperture extending downwardly from said face, a lower stem member having a threaded recess in its upper face and a removable 10 bowl having a threaded extension passing through the aperture of said upper member and engaging with said recess to draw said upper and lower members into clamping contact.

5. In a tobacco pipe the combination of a 15 removable bowl member having a threaded extension on its lower face, a lower stem member having a threaded recess in its upper face receiving said extension, an upper stem member having an aperture of diameter greater than the diameter of said extension said aperture surrounding said extension to leave a cooling chamber, and connecting conduits between said chamber and the interior of said bowl. 20

Signed at Liverpool in the county of Lancashire, this 27th day of November, 1925.

DAVID BARKER. 25
